UNITED STATES PATENT OFFICE.

EUGENE MCCOY, OF STAPLES, MINNESOTA.

PACKAGE-CARRIER FOR AUTOMOBILES.

1,342,557.

Specification of Letters Patent.

Patented June 8, 1920.

Application filed January 10, 1919. Serial No. 270,468.

To all whom it may concern:

Be it known that I, EUGENE MCCOY, a citizen of the United States, residing at Staples, in the county of Todd and State of Minnesota, have invented certain new and useful Improvements in Package-Carriers for Automobiles; and I do hereby declare the following to be a full, clear, and exact description of the invention, such as will 5 enable others skilled in the art to which it appertains to make and use the same.

My invention has for its object to provide an extremely simple and highly efficient package carrier for the running board of an automobile; and to such ends, generally stated, the invention consists of the novel devices and combinations of devices herein-after described and defined in the claims.

The invention is illustrated in the accompanying drawings, wherein like characters indicate like parts throughout the several views. Referring to the drawings;

Figure 1 is a fragmentary view in side elevation showing portions of the automobile and showing my improved package carrier applied to the running board thereof;

Fig. 2 is a plan view of the parts shown in Fig. 1;

Fig. 3 is an enlarged transverse vertical section on the line 3—3 of Fig. 1.

Fig. 4 is a transverse section on the line 4—4 of Fig. 3; and

Fig. 5 is a plan view of the parts shown in Fig. 4.

Of the parts of the automobile it is only necessary for the purposes of the case to particularly note the running board 6 which is of the customary construction.

The carrier comprises an upright longitudinally extended skeleton frame which, as preferably constructed, comprises end posts 7, a top rail 8 and bars or rods 9. The posts 7 and top bar or rail 8 are preferably tubular, being made of wrought iron or steel tubing or pipe sections, the ends of the top bar 8 being connected to the tops of the posts 7 by suitable elbows 10. The bars or rails 9, at their ends, are connected to the intermediate portions of the posts 7. The lower ends of the posts 7 are swiveled in the sleeve-like heads 11 of horizontal crank arms 12, which crank arms are pivoted on bolts or machine screws 13 passed through perforations therein and shown as engageable at their lower ends with nuts 14. The crank arms 12 rest on the upper faces of

channel-shaped anchoring bars 15. These anchoring bars 15 rest upon and extend transversely of the running board 6, and at their ends, are provided with bolt holes 16 through which, and the running board, nut-equipped bolts 17, or screws, are adapted to be passed to securely anchor said bars 15 to the running board. Said anchoring bars 15 are provided with longitudinal slots 18 through which the bolts 13 are passed, and preferably, and as shown, the nuts 14 are provided with reduced angular portions 14^a that slide, but do not turn within the said slots 18. The sleeves 11 are provided with set screws 11^a which, when tightened, hold the crank arms against rotation, in respect to the post 7.

With the above described arrangement, the slots 18 provide for adjustments of the frame 8—9 toward and from the side of the automobile, and by oscillatory movements of the crank arms 12, the said frame may be set in farther and out farther than would be permitted simply by the slots. To illustrate, the frame can be slid inward as far as the nuts 14 will go in the slots 18 and then the cranks may be turned inward to throw the frame close against the side of the machine, as shown by dotted lines in Fig. 3; and, on the other hand, the nuts 14 can be moved outward to their limit in the slots 18 and then the cranks 12 can be turned outward so as to set the frame approximately at the outer edge of the running-board, as shown by full lines in Fig. 3. Of course, the holding frame may be set in any desired intermediate position and also one end may be set farther out than the other. By these adjustments, the carrier can be adjusted to hold packages of different sizes; may be easily extended or projected for use, or set to its inner position where it will not be in the way and will leave the running board free for use in the ordinary way. Also, the device may be easily and quickly applied to the automobile.

What I claim is:

1. A package carrier for the running boards of automobiles, comprising anchor bars securable to a running board transversely thereof, and an upright frame secured to said anchor bars and laterally adjustable while attached thereto in a direction longitudinally of said anchor bars, whereby the width of the carrying space in the applied carrier may be varied.

2. A package carrier for the running boards of automobiles, comprising anchor bars securable to a running board, an upright frame, and crank members pivotally connected to and supporting said frame and themselves connected to said anchor bars for combined oscillatory and sliding movements.

3. The combination with an automobile, of a package carrier applied to the running board thereof and comprising an upright frame, and connections between said frame and runningboard permitting said frame to be laterally adjusted while connected thereto, to be moved to and from an operative 15* position, and to be secured in different operative positions to vary the carrying space.

4. In a package carrier for the running-boards of automobiles, the combination with anchor bars securable to the running board 20 transversely thereof and having longitudinal slots, nut-equipped bolts slidable in said slots, crank arms pivotally mounted on said bolts, and an upright frame having end

posts pivotally mounted in the free ends of said crank arms and movable to and from 25 operative positions by combined sliding and pivotal movements of said crank arms.

5. In a package carrier for the running-boards of automobiles, the combination with anchor bars securable to the runningboard 30 transversely thereof and having longitudinal slots, nut-equipped bolts adjustable in said slots, crank arms pivoted on said bolts and provided with bearing sleeves at their free ends, an upright frame having end 35 posts pivotally mounted in said bearing sleeves, and set clamping devices applied to said sleeves for rigidly securing said posts in said sleeves.

In testimony whereof I affix my signature 40 in presence of two witnesses.

EUGENE McCOY.
